INVENTOR
Edwin Sargent,
BY
Geo. A. Sargent
HIS ATTORNEY

UNITED STATES PATENT OFFICE.

EDWIN SARGENT, OF NORTH ARLINGTON, NEW JERSEY.

SCUPPER.

Application filed July 1, 1926. Serial No. 119,845.

This invention relates to scuppers or gutters, and has reference, particularly, to improvements in the type of scupper disclosed in Patent No. 1,104,806, dated July 28, 1914, 5 of which I am the owner.

In the aforesaid patent valves are located at the receiving and discharge ends of the scupper, and one of the objects of my invention is to provide novel means for mounting such valves. As both valves are capable of shifting in one direction by the fluid passing through the scupper and must automatically return to normal or closed position, it is imperative that they be mounted so as to 10 swing very freely and, when in their closed position, be so arranged that there will be no possibility of drafts or the elements entering the building through the scuppers. My invention provides for these functions in a 15 very simple and efficient manner.

Another object of my invention is to provide means of a simple character enabling the removal of the inner valve or damper with facility for the purpose of renewing it 20 if, at any time, it should be damaged.

A further object of my invention is to provide means for preventing any article, such as a box or case, being shoved against the mouth of the receiving end of the scupper and accidentally or purposely closing the entrance and preventing the ready escape of water from the building.

Other objects and advantages of my invention will be apparent as this specification proceeds, and details of the invention will be hereinafter set forth and pointed out in the claims.

For a clear understanding of the invention, drawings have been provided in which:

Figure 1 is a view in central longitudinal section through the scupper, the latter being shown in place in the wall of a building, the valves being indicated in their open positions by broken lines;

Figure 2 is a top plan view with a fragment broken out at the discharge portion of the scupper, and showing the wall of the building in section;

Figure 3 is a view in elevation looking at the inside of the removable frame and showing part of the valve broken away;

Figure 4 is a fragmentary sectional view taken on line 4-4 of Figure 1;

Figure 5 is a view in end elevation of the parts shown in Figure 3; and

Figure 6 is a perspective view of one end

of the removable frame, looking toward the inside, the frame being shown without the cross-bars.

Referring to the drawings, the scupper comprises a hollow casing 10, which is set into the wall 11 of any building or structure, at the floor line 12. The scupper is preferably given a pitch, as illustrated in Figure 1, to insure proper drainage from the floor 60 of the building. At the inner side of the wall 11, the scupper has a large receiving portion or mouth 13 adapted to be normally closed by the valve 14. The receiving portion 13 is connected by a tapered intermediate portion 15 with the restricted discharge portion 16. As illustrated, the area of the cross-section of the passage in the receiving or mouth portion is considerably greater than that of the discharge portion. 65 The discharge portion is adapted to be normally closed by a valve 17. The receiving portion is located with its bottom inner surface at or about the floor level, and the discharge portion projects beyond the outside 70 of the wall. The device acts as a drain and is particularly effective where a building is flooded by water during a fire or by an accidental or premature opening of the sprinkler system in a building. 75

One of the important features of my invention is the method of mounting the valves 14 and 17. In the prior Patent No. 1,104,806, these valves are mounted on pins which are riveted or otherwise secured in 80 the casing 10. Difficulty is experienced in aligning the holes for these pins, and in cases where they are not properly aligned the valves will have a tendency to stick with disastrous results. If the valves are opened 85 and stay open, the elements will enter and employes will stuff them up, thus frustrating the entire object of installing the scuppers. In case of a fire in an adjoining building, the open scupper would act as a flue and readily form an entrance for the flames. If the valves of the scuppers do not swing 90 freely at a time of emergency, when it is desired to free the building of water, the results again are very costly. The damper at the receiving portion is quite apt to become damaged or broken. Mounted as is disclosed in said patent, it would be very impractical and costly to install a new damper because the ends of the pin on which 95 it is mounted are entirely covered by the wall construction. The valve for the re-

ceiving portion in said patent has no seat. The valve, therefore, has to fit very snugly in the casing to insure keeping it weather-tight, and this naturally means the possibility of it binding.

The invention contemplates a simple and efficient construction to overcome all of the foregoing objections. The mounting of the valve 14 in the mouth or receiving portion 10 will first be described. The receiving portion of the scupper is flanged at 18. In setting the scupper in the wall of the building, it is desirable to have the flange 18 project into the building. A frame 19 having bolt holes 20 is secured by bolts 21 to the flange 18. At each end of the frame, adjacent the side walls of the receiving portion, is a sloping seat 22. The angle of the slope on these seats is such that, when the scupper is in place in the wall, the valve 14 will hang against the slope. A lug 23 is formed at the upper end of the seats adjacent the side walls of the receiving portion. The lugs have a notch 24 in which the projecting ends of the rod 25 in the valve 14 may rest. These lugs 23, as shown, are located close to the top wall of the scupper. When the trunnions, formed by the projecting ends of the wire or rod 25, are in place in the notches 24, the 30 top wall will prevent their displacement. As shown particularly in Figures 3 and 6, the width of the lugs 23 is about one-half of the width of the seats 22. The result of this is that the valve 14 has ample clearance 35 in relation to the side walls of the receiving portion, and the seats 22, in addition to acting as seats, will prevent any drafts passing the valve 14. As shown in Figure 1, the valve, having a slight clearance at its lower 40 part, will not bind and will always function properly; and it is suspended so that the slightest pressure of water from the inside will open it and, at the same time, it will act as an effective barrier for anything coming from the outside. It can be readily seen that, by releasing the nuts on the bolts 21, the frame 19 may be removed and a new valve easily slipped in place. Ribs or bars 45 26 are shown extending from top to bottom of the frame. These ribs or bars 26 have rugged protuberances 27 extending therefrom varying distances into the room. The purpose of the ribs and protuberances is to 50 protect the damper 14 and to act as stops in preventing any object, such as a box or a case, being placed against the mouth of the scupper and impeding the flow of water through the scupper.

The mounting of the valve 17 in the discharge portion of the scupper will now be described. This valve which acts as a weather guard may be of heavier construction than the valve 14. It has a pair of trunnions 28 formed on its upper corners. 55 These trunnions are mounted in short bush-

ings 29 which, in turn, are mounted in notches in the upper parts of the side walls of the discharge portion of the scupper. In its normally closed position, the valve 17 is adapted to rest against a seat 30 formed in the side walls. The seats 30 give the same advantage as the seats 22, that is, they allow the valve 30 to have ample clearance and do not impair its efficient operation. The lower lip of the valve may be offset to cooperate 75 with a like portion in the lower wall of the discharge portion, and may also be weighted to render it more effective. A slot or opening 31 is formed in the upper wall of the discharge portion. In assembling, the valve 80 is slipped through said slot and its trunnions, with their bushings, are dropped into their respective notches. A closure plate 32 is provided for the slot, the purpose of which is to prevent any dirt from the wall 85 dropping in and interfering with the action of the valve and also to confine the trunnions of the valve in their notches. The closure plate has its ends 33 bent down over the sides of the discharge portion and a pair 90 of prongs 34, punched from the plate, are bent down and under the top wall to hold the plate in position.

In some cases it may be desirable to form the frame 19 without the ribs or bars 26. 95 This is illustrated in Figure 6. It will be obvious that one skilled in the art might make changes, in details and form, from the preferred embodiment of the invention illustrated and described, and such changes are 100 within the range of my invention and are contemplated as coming within the scope of the appended claims.

Having thus described my invention, what I claim and desire to secure by Letters 105 Patent is:

1. In a scupper, the combination of a hollow casing, adapted to be located in a wall at the floor level for draining water from the floor; a frame removably secured at the inner end of said casing; a series of bars across said frame, said bars having protuberances thereon to prevent any object being placed against the inner end of the casing and closing it off; and a valve pivotally mounted on said frame, said valve being adapted to substantially close the inner end of the casing.

2. In a scupper, the combination of a hollow casing, adapted to be located in a wall 120 at the floor level for draining water from the floor; a frame removably secured at the inner end of said casing; a valve pivotally mounted on said frame, said valve being adapted to substantially close the inner end 125 of the casing; a second valve adapted to substantially close the outer end of the casing; a seat formed in the casing on which said second valve will normally rest in the closed position; an opening in the upper wall of 130

the casing through which the valve may be slipped; and a closure for the same.

3. A scupper comprising a casing having, at its receiving end, a removable frame provided with a plurality of guards of varying dimensions for preventing obstructions being placed at the receiving end of the scupper; a valve mounted on the frame and freely movable relatively thereto in the direction of flow of fluid through the scupper; and means for normally closing the discharge end of the scupper.

4. In a scupper, the combination of a hollow casing, adapted to be located in a wall of a building at the floor level for draining water from the floor, a valve adapted to substantially close the outer end of said casing, a seat formed in the casing on which said valve will normally rest in the closed position, an opening in the upper wall of the casing through which the valve may be slipped, and a closure for said opening.

5. In a scupper, the combination of a hol-

low casing, adapted to be located in a wall of a building at the floor level for draining water from the floor, said casing having a substantially large receiving portion with parallel side walls, a portion tapering away from said receiving portion and a restricted discharge for said receiving portion, a valve pivotally mounted in said receiving portion, said valve having an area substantially that of the cross section of said receiving portion and capable of being opened to its full capacity in said receiving portion, a valve seat for said valve, a second valve adapted to substantially close the outer end of said casing, a seat formed in the casing on which said second valve will normally rest when in the closed position, an opening in the upper wall of the casing through which the valve may be slipped, and a closure for said opening.

In testimony whereof I affix my signature.

EDWIN SARGENT.
